UNITED STATES PATENT OFFICE.

LOREN O. CRENSHAW, OF LOS ANGELES, CALIFORNIA, ASSIGNOR TO MAGNETIC SIGNAL COMPANY, A CORPORATION OF CALIFORNIA.

DOUBLE-COIL OSCILLATING MOTOR.

1,347,209.

Specification of Letters Patent. Patented July 20, 1920.

Application filed May 7, 1919. Serial No. 295,795.

To all whom it may concern:

Be it known that I, LOREN O. CRENSHAW, a citizen of the United States, residing at Los Angeles, county of Los Angeles, and 5 State of California, have invented a new and useful Improvement in Signals Comprising a Double-Coil Oscillating Motor, of which the following is a specification.

My invention relates to signal devices and 10 particularly to signals which are peculiarly adapted for use on railway crossings for the purpose of warning traffic on the highway of the approach of trains along the railway. It may, of course, be used in other 15 situations and for other purposes.

In the form of my invention illustrated,

Figure 1 is a side elevation of my invention, the case being shown in section to better illustrate the invention.

20 Fig. 2 is a side view.

Fig. 3 is a diagram of connections.

In the form of my invention shown, a case 11 is provided, in the top of which is secured a stationary armature 12 and in 25 which is journaled a shaft 13. The shaft 13 extends through the side of the case 11 and carries a hub 14 on the upper end of which is secured a rod 15 carrying a display 16 and on the lower end of which is secured a rod 17 carrying a pendulum 18. Rigidly secured on the shaft 13 are two 30 magnets 20 and 21 which have the form shown in Fig. 3 and which are spaced in relationship to the armature as shown in 35 that figure. On the magnet 20 is an energizing coil 24 and on the magnet 21 is an energizing coil 25; these coils being connected together at one terminal; their junction being connected through a wire 26 to contact 40 making device 27 which is connected to one terminal of a battery 28 or other source of power. The other terminals of coils 24 and 25 are connected to moving contacts 30 and 31 which are carried on suitable insulation 45 secured on the magnets 20 and 21 and making electrical contact with stationary contact fingers 32 and 33, these contact fingers being secured by common casting through a wire 36 to the other side of the battery 28. 50 Contact 32 is rotated in clockwise direction by means of spring 40, the amount of this rotation being governed by set screws 41. The magnets 20 and 21 are so set with rela-

tion to the shaft 13 that the magnet 20 is considerably nearer the armature 12 than 55 the magnet 21 when the signal is in its central position, as shown in Fig. 1.

Whenever the contact device is closed with the parts in the position shown in Fig. 1, which is the position the signal assumes 60 when the current is cut off, both of the coils 24 and 25 are energized and both exert an attraction on the armature 12; the attraction of the magnet 20 is, however, due to its nearer position much greater than the 65 attraction of the armature 21 and the shaft 13 is therefore rotated in a clockwise direction, the magnet pulling in under the armature 12. This continues until the set screw 41 of contact finger 32 arrests its motion and 70 opens the circuit between contact finger 32 and movable contact 30, thus deenergizing the coil 24, the signal thereafter swinging by its own momentum through a considerable 75 arc during which there is an attraction between the magnet 21 and the armature 12, although this attraction, due to the distance between the armature and the magnet is quite small. As, however, the signal swings 80 back toward the central position, after having completed its arc of travel, this pull increases and continues until the signal 85 swings slightly past its central position and the contact is broken between the finger 33 and the contact 31. The alternate pull of 85 the magnets 20 and 21 continues until the circuit is broken at the contact making device 27.

I claim as my invention:

A double coil oscillating motor comprising 90 a shaft; a pendulum dependent from said shaft; a magnet casting secured to said shaft and having two radial pairs of limbs both limbs of each radial pair being located in a radial plane to which said shaft is perpendicular, these planes being parallel to each other, the limbs in each radial plane being located in angular relationship to each other but so disposed as to form, with one of the limbs in the other radial plane, an axial pair 95 both of the limbs of each axial pair being in a single axial plane which also contains the axis of said shaft, said axial planes forming a dihedral angle; an armature so located 100 that it can come into magnetic relationship 105 with each of said axial pairs as said shaft is

rotated but being somewhat nearer one of said axial pairs than the other when said pendulum is in its lowest position; two coils each surrounding one of said limbs but being located in different radial and axial planes; means for energizing both of said coils; and means for deenergizing each coil

as the limb on which it is placed comes into its position of maximum magnetic pull on said armature.

In testimony whereof, I have hereunto set my hand at Los Angeles, California, this 1st day of May, 1919.

LOREN O. CRENSHAW.
